(57) **CLAIM**

The ornamental design for a cargo container footer, as shown and described.

DESCRIPTION

FIG. 1 is a top, right isometric view of a cargo container footer showing my new design.

FIG. 2 is a front elevation view thereof.

FIG. 3 is a rear elevation view thereof.

FIG. 4 is a left side elevation view thereof.

FIG. 5 is a right side elevation view thereof, and,

FIG. 6 is a top plan view thereof.

The portions of the design shown in broken lines are for environmental purposes only and form no part of the claimed design.
